Primary Examiner — Marianne Pandozzi*(74) Attorney, Agent, or Firm* — Foley & Lardner LLP(57) **CLAIM**

The ornamental design for a steam injecting brewer, as shown and described.

DESCRIPTION

FIG. 1 is a top perspective view of a steam injecting brewer showing my new design;

FIG. 2 is a top perspective view thereof with lid in open position;

FIG. 3 is an exploded perspective view thereof;

FIG. 4 is a front elevational view thereof;

FIG. 5 is a front elevational view thereof with the lid in open position;

FIG. 6 is a right side elevational view thereof; and,

FIG. 7 is a right side elevational view thereof with the lid in open position.

The steam injecting brewer design is characterized by the stout shape, round contours, incorporation of a circular bowl with spout, and a protruding half-sphere with lateral concave hole.
